UNITED STATES PATENT OFFICE.

THOMAS WALTER FRED, OF CHATTANOOGA, TENNESSEE.

DESIGN FOR A BOX CASING.

Application filed November 26, 1924. Serial No. 11,489. Term of patent 7 years.

To all whom it may concern:

Be it known that I, THOMAS WALTER FRED, a citizen of the United States, residing at Chattanooga, in the county of Hamilton and State of Tennessee, have invented a new, original, and ornamental Design for Box Casings, of which the following is a specification, reference being had to the accompanying drawing, forming part thereof.

Figure 1 is a plan view of a box casing,

the box which it surrounds being shown in dotted lines;

Figure 2 is an edge view thereof with the box shown in dotted lines.

What I claim is:

The ornamental design for a box casing or similar article of manufacture substantially as shown and described.

THOMAS WALTER FRED.
